UNITED STATES PATENT OFFICE.

MARCUS I. BROCK, OF WAYNE, PENNSYLVANIA

WHEEL-HUB.

1,228,398.

Specification of Letters Patent. Patented June 3, 1917.

Application filed July 21, 1914. Serial No. 852,135.

To all whom it may concern:

Be it known that I, MARCUS I. BROCK, a citizen of the United States, residing at Wayne, in the county of Delaware, State of Pennsylvania, have invented a new and useful Wheel-Hub, of which the following is a specification.

The invention relates to improvements in hubs for vehicle wheels. The object is to provide improved means for securing the removable to the fixed hub element to provide positive engagement locking over such large surfaces as to minimize wear and to provide continuous coincidental compensation therefor.

The invention comprises means for positively preventing relative rotative and longitudinal movement between said elements and also means for taking up wear between said two elements continuously and coincidentally.

Referring to the drawings, which illustrate merely by way of example, suitable embodiment of my invention—

Figure 1 is a front elevation of an improved hub comprising my invention.

Fig. 2 is a side elevation of same.

Fig. 3 is a section on line 3—3 of Fig. 1, on an enlarged scale.

Fig. 4 is a section on line 4—4 of Fig. 3.

Figs. 5 and 6 are fragmentary views in perspective, showing the interlocking means between said hub elements.

Similar numerals refer to similar parts throughout the several views.

The fixed hub element 7 is shown as being of true cylindrical formation and is provided with the conical ring member 8 secured to the flange 9 by the bolt 10 which also secures the brake drum 11. As stated, this inclined

enlargement 8 is shown in the drawings as a separate or an additional piece secured to the fixed hub 7. It is obvious however that it may be formed integral therewith. The surface of the inclined periphery of 8 is provided with longitudinally and inwardly (or outwardly) extending tapered formations 12. The removable hub element 13 is shown with a cylindrical formation longitudinally, and provided with the flaring portion 14 of substantially corresponding inclination with that of the periphery of extension 8 of the

fixed hub. This portion 14 of the removable hub element is provided with longitudinally and inwardly (or outwardly) extending tapered formations 15 which register and co-operate with the similarly extending tapered formations 12. As shown in Fig. 3 sufficient room or space is provided between the flanges 15^a and 16 when the extensions 14 and 8 are in close engagement to permit of said flanges 15^a and 16 being brought into closer relative position to take up any wear between extensions 14 and 8. The movable and fixed hubs 7 and 13 are brought into operative relationship and relative longitudinal movement therebetween is prevented by any suitable means such as the nut 17 operating through ring or washer 18 which presses against the ends of said hub element. It will be obvious that the co-operating longitudinally and inwardly or outwardly extending tapered formations on the fixed and movable hub elements may be reversed as to the direction of taper.

It will further be obvious that the object of my invention may be obtained in accordance with the principle illustrated, not only by the use of tapered formations of curved cross-section, but also by formations of any other cross-section, so that at least one surface converges toward one or more of the other surfaces, and provides continuous coincidental compensation for wear and the formations of the two hub elements co-operate with each other; and it will be obvious further that the tapered surface between the inwardly or outwardly extending formations may be used as a further means of locking (but not by engagement) the two hub elements, but is not essential to this invention.

Figs. 5 and 6 show alternative arrangements which are in many respects substantial equivalents. An essential feature of the invention is that the co-operating conical or tapered feature means for taking up wear is operatively and essentially combined with the feature of positively locking against relative rotation of the two hub elements.

What I claim is:—

A fixed hub element comprising a substantially cylindrical body, a relatively short

100

2
tapering shell surrounding and secured to said cylindrical body and provided with a plurality of parallel tapering projections, a movable hub element of cylindrical formation having a flaring rear end to receive the tapering shell and having interiorly disposed

tapering recesses for coöperating with the tapering projections.

MARCUS I. BROCK.
